UNITED STATES PATENT OFFICE.

ROBERT WEIMAR, OF SEATTLE, WASHINGTON.

TRANSPOSITION PIN.

Application filed August 31, 1927, Serial No. 216,518. Renewed February 2, 1929.

My present invention relates to an improved transposition pin used in the installation of electric, telephone, telegraph and similar lines in connection with the insulator or insulators for holding the conductors or wires of the lines. The primary object of the invention is the provision of an interchangeable device for attachment to the cross arm of the pole or other wire support where 5 by either a single insulator or conductor-support may be supported above the cross arm or support, or a duplex insulator may be used, one above and one below the cross arm or support to which the wires are attached 10 as usual.

By the utilization of the device of my invention both time and labor are saved in the erection and installation of the lines, the material is provided in standardized parts 20 that are adapted for use in varying conditions, and the workman is enabled to perform functions with facility and convenience. The invention consists in certain novel combinations and arrangements of parts as will 25 hereinafter be more fully set forth and claimed. In the accompanying drawings I have illustrated one complete example of the physical embodiment of my invention wherein the parts are combined and arranged 30 both as a single and as a duplex conductor holder or insulator, according to the best modes I have so far devised for the practical application of the principles of my invention.

Figure 1 is a view of a portion of a cross arm with a single and a duplex conductor holder thereon arranged according to my invention.

Figure 2 is an enlarged sectional view of 40 one of the duplex conductor holders adapted to support a wire both above and below the cross arm or other support.

Figure 3 is a detail view of a single conductor holder showing the cross arm or support in section.

While the conductor holders and transposition pin are adapted for use in connection with various kinds of supports, for convenience of description I shall refer to the support 50 1 as the cross arm of a telegraph, telephone or power line pole to which the lines or wires are connected for support.

Two insulators, as 2 and 3 are shown one above and the other below the cross arm, 55 which are fashioned of glass or other non-conducting material with the usual annular

groove 4 for the wire, and the skirt 5 below for shedding water. As shown in Figure 1 the insulators may be used either above the cross arm, or both above and below the 60 arm in connection with a transposition pin which includes an upper bolt 6 having a flange or head 7 to rest upon the top face of the cross arm, and the lower, tubular or socket end 8 of the bolt extends through a hole 9 in the cross arm. The exteriorly threaded end 10 of the tubular bolt projects below the lower surface of the cross arm, and a nut 11 is used to clamp the tubular bolt in the hole 65 of the cross arm.

The bolt is provided with a polygonal portion 12 above its flanged head 7 to accommodate a wrench, which holds the bolt while the clamp nut 11 is being turned on the threaded end 10. Between the metal of the 70 bolt and the insulator 2 I provide a wooden plug or screw filler 13 which is threaded on the upper end of the bolt 6, and the insulator 2 in turn, is threaded on the exterior 75 threads of the wooden plug 13.

These described parts of the transposition pin provide for a single insulator or conductor holder used above the cross arm.

When the duplex insulators 2 and 3 are to be used both above and below the cross 80 arm, other elements are added, including a lower bolt 14 that is threaded into the internally threaded, tubular, part 8 of the upper bolt, and which is provided with a polygonal head 15 for the accommodation of a wrench 85 or other suitable tool. The lower bolt is also threaded to receive the wooden plug or sleeve 16 between the bolt and the insulator 3, and the bolt passes through an opening 17 in the top of the insulator. Between the insulator 90 and the clamp nut 11, a gasket 18 is interposed to afford a cushion to prevent breakage of parts when the wrench is applied to the head 15, the bolt of course being passed through the hole in the gasket as well as 95 through the hole in the nut 11. Thus the insulator 2 is supported in clamped position by means of the flanged head 7 and nut 11, and the insulator 3 is supported in clamped position by means of the transposition pin, including the bolt 14 threaded into the tubular 100 portion 8, and it will be apparent that the insulator 3 may be added with facility and convenience when needed.

Having thus fully described my invention, 110 what I claim as new and desire to secure by Letters Patent is—

1. The combination with a cross arm having a hole therethrough of a bolt having a tubular threaded portion projecting through said hole and an open center clamp-nut on the projecting part of the tubular bolt, a second bolt threaded into the tubular portion of the first bolt, and insulators supported on said bolts.
2. The combination with a cross arm of a transposition pin including a tubular,

threaded bolt portion having a head at one end and an open center nut at the other end of said bolt-portion, a bolt threaded into said tubular portion, an insulator carried by the second bolt, and means whereby the second bolt is turned to clamp the insulator against the open center nut. 15

In testimony whereof I affix my signature.

ROBERT WEIMAR.
